UNITED STATES PATENT OFFICE.

RICHARD CAREWELL, OF BROOKLYN, NEW YORK.

DESIGN FOR A PEAK-CAP.

53,288.

Specification for Design.

Patented May 13, 1919.

Application filed December 30, 1918. Serial No. 268,992. Term of patent 14 years.

To all whom it may concern:

Be it known that I, RICHARD CAREWELL, a citizen of the United States, and residing in Brooklyn, in the county of Kings and State of New York, have invented a new, original, and ornamental Design for a Peak-Cap, of which the following is a specification, reference being had to the accompanying drawing, forming part thereof.

Figure 1 is a top plan view of my newly designed peak cap;

Fig. 2 a side edge view thereof; and

Fig. 3 a bottom plan view thereof.

The essential element of my new design is a peak cap having a crown which is of angular or diamond-shaped form and a peak with one point of the crown extending forwardly over the central portion of the peak.

I claim:

The ornamental design for a peak cap as shown.

RICHARD CAREWELL.
